Primary Examiner — Sanjeev Paul(74) *Attorney, Agent, or Firm* — BACON & THOMAS, PLLC(57) **CLAIM**

The ornamental design for nose pads for eyeglasses, as shown and described.

DESCRIPTION

FIG. 1 is a front view of nose pads for eyeglasses showing my new design;

FIG. 2 is a back view thereof;

FIG. 3 is a top view thereof;

FIG. 4 is a bottom view thereof;

FIG. 5 is a right side view thereof;

FIG. 6 is a section taken along the line 6-6 in FIG. 1;

FIG. 7 is an enlarged view taken along the line 7-7 in FIG. 2;

FIG. 8 is an end section taken along line 8-8 of FIG. 7; and, FIG. 9 is a referential perspective view of the overall eyeglasses.

The broken lines shown in the drawings are included for the purpose of illustrating portions of the nose pads for eyeglasses that form no part of the claimed design.

1 Claim, 5 Drawing Sheets(56)
